ORBITING MASSAGE MACHINE

Earl McCaw, 525 Stockton St., San Francisco, Calif.
Filed Sept. 29, 1962, Ser. No. 224,929

3 Claims. (Cl. 128—46)

The invention, in general, relates to the art of body massage and more particularly relates to a light-weight, portable power driven applicator that can readily be self-manipulated or self-used to treat the body for promoting circulation and for enhancing suppleness of the body and its components.

Heretofore there has been but little attention devoted to the provision of a machine for increasing body suppleness by massage which could be manufactured inexpensively and sold within a non-prohibitive price range, and which could be employed by the individual to his own body without the help of others. In the main, most persons suffering from poor circulation with attendant aches and pains, or suffering from stiffness of joints, recurring cramps in the limbs and hands with soreness, have repeatedly or constantly employed professional masseurs to treat the body by rubbing or kneading the muscles about the stiff joints or cramped areas. The present invention is directed to the provision of a relatively inexpensive massaging machine that can be handled and manipulated as easily by the unskilled as the skilled for application to the body for desired periods of time to treat the same for pain, aches and the like as well as for nervous tension and tired feeling.

A primary object of my invention is to provide an orbiting massage machine which is capable of being applied by an individual to various portions or areas of his own body in nearly all cases of treatment.

Another important object of the present invention is to provide an improved orbiting massage machine of the indicated nature which is additionally characterized by its relatively simple construction, by its lightness in weight and by its low cost of use and maintenance.

A still further object of the invention is to provide an orbiting massage machine of the aforementioned character which is capable of being readily transported, which is power driven and can be plugged into any outlet from a source of standard 110-120 volt alternating current, and which can be employed by any adult person without assistance, in nearly all cases of body application, from professionals or other persons.

Other objects of the invention, together with some of the advantageous features thereof, will appear from the following description of a preferred embodiment of the invention which is illustrated in the accompanying drawings. It is to be understood, however, that I am not to be limited to the precise embodiment shown, nor to the precise arrangement of the component parts thereof, as my invention, as defined in the appended claims, can be embodied in a plurality and variety of forms.

Referring to the drawings:

FIG. 1 is a sectional elevational view of a preferred embodiment of the invention.

FIG. 1A is an enlarged fragmentary detail of a speed regulation switch for the motor of the machine where a variable speed motor is incorporated therein, such regulator switch being adapted to the inner end of one of the handles.

FIG. 2 is a fragmentary reduced perspective view of the preferred embodiment of my invention applied to the upper back of a person, and one of the few instances where the help of another is required.

FIG. 3 is another reduced perspective view of the machine, this view illustrating the application thereof by the individual to the lower back of her body.

FIG. 4 is still another reduced perspective view showing

2

the machine being applied by the individual to the back of her neck.

FIG. 5 is a reduced perspective view of the preferred embodiment of my invention in an inverted position, this view showing use of the machine at the lower back of an individual in partially reclined position.

FIG. 6 is still another reduced perspective view of the machine as applied by an individual to her right shoulder.

FIG. 7 is another reduced perspective view of the machine, in inverted position and illustrating the treatment of the feet by an individual without the aid of another.

FIG. 8 is a perspective view of the machine being applied by an individual to her knees.

FIG. 9 is another reduced perspective view of the machine in inverted position seated on a planar surface, this view illustrating how an individual can treat the calf of her leg without assistance from others.

FIG. 10 is a reduced perspective view of a preferred embodiment of the invention illustrating the application thereof by an individual to her hip.

FIG. 11 is a view similar to FIG. 10 but showing application of the machine to the stomach for treatment of the stomach muscles.

FIG. 12 is a further reduced perspective view of the machine, in an inverted position and illustrating how a person using both hands can apply the machine for treating excess fat under her chin.

In its preferred form, the orbiting massage machine of the present invention preferably comprises a rotatably mounted shaft, means for rotating said shaft, together with a member eccentrically mounted on said shaft for vibratory motion on rotation of said shaft and a yieldable pad having a concave outer surface secured to said member for orbital, vibratory motion with said member upon rotation of said shaft.

While I have depicted in the annexed drawings a variety of different uses of my improved orbiting massage machine for the treatment of the body and thereby stimulate blood circulation and enhance body suppleness so as to inhibit pain and aches in stiff muscles and joints as well as to render assistance toward the relief of body tiredness and nervous tension, it is to be understood that I am not to be limited in the utilization of my improved massage machine to those illustrated. For, it is quite within the purview of beneficial uses, in addition to the tendency to diminish fatty tissues and muscles about the stomach and hips or under the chin, as shown, as well as in other portions or areas of the body, and to treat the metatarsal bone under the guidance of an orthopedist, and like joints or bony regions of the body such as shoulder bones, or the several cervicals all under orthopedist guidance, also to effect treatment of certain regions of the head and forehead to lessen headaches and relieve anxiety concerning vision and hearing.

As particularly illustrated in FIG. 1 of the annexed drawings, I provide a housing 11 which preferably is fabricated of a light-weight metal, such as aluminum, and which defines a relatively large interior compartment 12 for confining an electric motor 13 including an armature 14 and windings 16. Any suitable mounting means for the motor 13 can be employed, such as spring-loaded rods 17 and 18 extending through metal laminations for the windings 16 on opposite sides of the motor armature 14, together with coil springs 19 and 20, respectively, encircling the rods 17 and 18 and confined between the housing 11 and a pair of nuts 21 and 22 threaded on the rods 17 and 18, respectively, and engaging the metal laminations for the windings, as shown. The outer ends of the rods 17 and 18 may extend into recesses 23 and 24 formed in a cap 25 for the housing and are threaded to receive the binding nuts 27 and 28, respectively, which are counter-sunk

within the recesses of the cap, all as shown in FIG. 1. This spring mounting of the motor is effective in dampening the noise of the motor.

The present embodiment of my invention is preferably so formed as to provide opposed interior sockets 31 and 32 within the housing 11 for the reception and confinement therein of suitable bearings 33 and 34, respectively, such as ball bearings, in which motor shaft 36 is journaled. As shown, the motor shaft is extended through and beyond the socket 32 as well as through and beyond an axially arranged cooling fan 38 which is keyed to shaft 36, and I eccentrically mount on a reduced section 39 of motor shaft 36 another ball bearing 41. The reduced section 39 of the shaft is keyed or otherwise securely fastened to the bearing 41 so that the bearing 41 moves with the rotation of the shaft 36; movement of such bearing and the socket-defining member 42 in which the bearing 41 is secured being of a compound oscillatory and rotary nature within the larger socket 43 formed within the body of the fan 38 which is fastened to the motor shaft 36, thus to rapidly vibrate the member 42.

In accordance with my invention, I detachably mount on the vibratory member 42, by means of suitable metal screws 44, a yieldable pad, designated generally by the reference numeral 46 and including a cushion 47 of sponge rubber which is preferably in an elongated rectangular shape having a concave outer surface, as indicated at 48. Conveniently, the cushion 48 is bonded or otherwise attached to a body core 49 fabricated of wood or hard rubber, which in turn is bonded or otherwise secured to a metal plate 51 having a plurality of openings therein for passing a plurality of screws 52 for threadedly engaging the core 49. I preferably encase the hard rubber core 49 and the sponge rubber cushion 47 in a suitable leather covering 53 to avoid likelihood of damage to the otherwise exposed rubber cushion 47. By such mounting of the pad 46, the vibratory motion accorded to the member 42 upon rotation of the motor shaft 36 is transmitted directly to the cushion or pad 46. A suitable electrical cord 54 is provided for connecting the motor windings 16 to a source of electrical energy, not shown, which may be that normally supplied on a conventional 110-120 volt alternating current circuit.

As shown in FIG. 1 as well as in the various reduced showings of the machine in the other views, I provide a series of radially arranged handles or grips 56, 57, 58 and 59 for the machine, which may be detachably secured to the housing 11 and which conveniently may take the form of hollow tubes 61, fabricated of aluminum or the like, covered with tubular rubber casings 62 which are press-fitted over the aluminum shafts or tubes 61 much in the manner of forming hand grips on bicycle handles or steering means. The electrical cord 54 may conveniently be extended through one of such grips, say the grip 57, as shown in FIG. 1. The circuit, not shown, can be completed to ground by means of a short conductor 63 extending from the cord 54 to a screw 64 threaded into the aluminum tube 61 of the handle grip 57.

As shown in FIG. 1A, the handle 57 is provided with a switch, generally designated by the reference numeral 66 for opening and closing the electrical circuit containing the motor 13 and thus controlling the operation of the vibratory member 42 and its attached pad or cushion 47. The switch 66 may take the form of an annulus 67 encircling and rotatably mounted on the hand grip. If a variable speed motor 13 is employed, the switch contacts, not shown, can be three in number so that the switch 66 can be thrown to any one of the three contacts, indicated generally by the reference numbers 1, 2 and 3 on the annulus 67, so as to rotate the motor at constant low speed, or at constant medium speed, or at constant high speed, all in the conventional man-

ner and at the will of the user of the machine and depending upon the area of the body massaged with the machine.

In the annexed drawings, I have depicted various applications of the orbiting massage machine of my invention to the human body. In FIGS. 2, 3, 4, 5 and 6, there are illustrated sequentially the treatment of the upper back, the lower back, the back of the shoulders, the small of the back and an area at the front of the right shoulder. All of these areas may have suffered severe strain with accompanying recurrent or constant pain as a result of a so-called whiplash in an automobile accident, such as a rear end collision. After examination by an orthopedist, physical therapy may be recommended by him including body massages at the areas indicated in these views. My improved massaging machine lends itself admirably to such physical therapy since the concave surface 48 of the yieldable pad 46 conforms to the body areas involved and the vibratory motion accorded to such yieldable pad on operation of motor 13 sets up body movements in those areas, stimulates the circulation of the blood and generally tends to increase suppleness of these body areas and to relieve nerve tension. The machine can also be used effectively, as indicated in FIGS. 2 and 3 to relieve soreness and aching back resulting from lifting strains, and will tend to obviate a general tiredness of the body. The views of FIGS. 8, 9, 10, 11 and 12 illustrate use of the orbiting massage machine of the present invention for muscle toning as well as the treatment of excess fat areas of the body for reducing exercises. As shown in FIG. 8, the machine is being applied to an area above the knees so as to tend to tone down excess fat tissue in that area; in FIG. 9, there is depicted the application of the machine to the calf of the leg for a similar purpose; and in FIGS. 10 and 11, there are shown applications of the machine to the hip area and to the stomach, respectively, likewise to treat such areas for undue fatty conditions and for reducing exercises. Similarly, the view of FIG. 12 shows application of the machine to the fatty muscles under the chin, such treatment tending to remove excess tissue in such area. In FIG. 7, the machine is shown seated on a planar surface with the pad 46 upright; this view illustrating vibratory treatment of the metatarsal bone of each foot to ease the stiffness thereof and inhibiting or tending to inhibit aching thereof.

In all of the views of FIGS. 3-12 inclusive, it will be noted that the orbital massage machine of the present invention can be handled and manipulated by an individual treating his own body; it being only rarely necessary, such as in applying the machine to the upper back, to have the aid of another person in handling the machine. It also is to be especially noted that the machine may be positioned angularly in relation to the body and in relation to a support, such as indicated in FIG. 5 where the person using the machine merely leans against the vibratory pad 46 of the machine by assuming a partially reclining position of the body. Also, that the massage machine may be inverted and seated on the grips 56, 57, 58 and 59 with the vibratory pad 46 uppermost and parallel with the surface on which the grips are seated, as illustrated in FIGS. 7 and 9, with the person applying the machine either standing or in a reclined position. The machine, being of light weight and being provided with a plurality of radially arranged grips, can be readily lifted, applied and manipulated by even an unskilled person without likelihood of injury.

It is to be understood that the appended claims are to be accorded a range of equivalents commensurate in scope with the advances made over the prior art.

I claim:

1. An orbiting massage machine comprising a housing, a motor rotatably mounted within said housing, a shaft with a shaft extension connected to and adapted to be

rotated by said motor upon rotation thereof; said shaft extension projecting beyond one side of said housing, a member eccentrically mounted on said shaft extension for vibratory movement upon rotation of said shaft and said shaft extension, an elongated yieldable pad having a concave exterior surface connected to said member for vibratory movement therewith and for engaging curved areas of the human body while undergoing vibratory movement to stimulate circulation and suppleness of the body, and at least three hand grips on the other side of said housing for enabling a person to apply said pad while undergoing vibratory movement to selected areas of the body; said plurality of hand grips serving the dual function of supporting said housing on a planar surface in an inverted position.

2. An orbiting massage machine comprising a rotatably mounted prime mover, means for rotating said prime mover, a shaft with a shaft extension connected to and adapted to be rotated by said prime mover, a member eccentrically mounted on said shaft extension for vibratory movement upon rotation of said shaft extension, an elongated yieldable pad detachably secured to said member for movement in unison with said member; said yieldable pad having a concave exterior surface for engaging and conforming to curved areas of the human body to which said pad is applied while undergoing vibratory movement whereby circulation may be stimulated and body suppleness may be increased, and at least three hand grips arranged in spaced relationship about said prime mover for enabling a person to apply and to hold said 30

other's body as well as to seat the motor on a planar surface with said yieldable pad presented above the planar surface for resting a limb thereon.

3. An orbiting massage machine comprising a housing, a motor rotatably mounted within said housing, means for rotating said motor, a shaft with a shaft extension connected to and rotated by said motor; said shaft extension projecting beyond said housing, a member eccentrically mounted on the projecting portion of said shaft extension for vibratory movement upon rotation of said shaft extension, an elongated yieldable pad on said member for vibratory movement in unison therewith; said yieldable pad having a concave exterior surface for engaging and conforming to curved areas of the human body to which said pad is applied while undergoing vibratory movement whereby body muscles may be toned and body suppleness may be increased, and at least three hand grips on and radially extending from said housing to enable a person to apply said pad while undergoing vibratory movement to selected areas of his own or another's body as well as to enable said housing to be supported on a planar surface with said pad above said surface.
